UNITED STATES PATENT OFFICE.

EMIL M. PERHÁCS, OF BROOKLYN, AND FRANZ NEUMÜLLER, OF NEW YORK, N. Y.

CATERER'S WAGON.

SPECIFICATION forming part of Letters Patent No. 275,516, dated April 10, 1883.

Application filed July 15, 1882. Renewed February 28, 1883. (No model.)

To all whom it may concern:

Be it known that we, EMIL M. PERHÁCS, of Brooklyn, in the county of Kings and State of New York, and FRANZ NEUMÜLLER, of the 5 city, county, and State of New York, have invented certain new and useful Improvements in Caterers' Wagons, of which the following is a specification.

This invention relates to an improved caterer's wagon by which warm meals of all kinds may be sent out and supplied to families living at some distance from the central kitchen, the wagon being more specially designed to supply people of moderate means at the lowest possible rate; and the invention consists of a caterer's wagon which contains a refrigerator back of the driver's seat and two hot-water tanks, closed by covers, the water in the same being heated by steam or hot-water circulation 20 from a furnace at the rear part of the wagon. The tanks are subdivided by partitions into cellular spaces, each of which receives a cylindrical tray of the well-known construction.

In the accompanying drawings, Figure 1 represents a vertical longitudinal section of our 25 improved caterer's wagon. Fig. 2 is a plan view of the same, partly in horizontal section on line *x x*, Fig. 1; and Fig. 3 is a vertical transverse section of the same on line *yy*, Fig. 1.

Similar letters of reference indicate corresponding parts.

Referring to the drawings, A represents a covered spring-cushioned wagon of the usual dimensions, which is provided back of the driver's seat with a refrigerator, B, which extends from side to side, and with two side tanks, C, of sheet metal, which extend throughout the full length of the wagon, from the refrigerator to the rear end thereof. The door B' of the 35 refrigerator opens at the rear side into a central passage or space, D, between the longitudinal tanks. These tanks are filled up to a certain height with water that is kept hot by steam-pipes E, connected by branch pipes E' to a small boiler, F, in which steam is generated, said boiler being heated by a furnace, G, arranged at the rear end of the wagon, below the bottom of the same, as shown clearly in Figs. 1 and 3.

In place of heating the water in the tanks 45 C by steam, it may be heated by circulating the

hot water first from the boiler into one of the tanks and then into the other and back again to the boiler, or the water may be heated by any other approved means.

The tanks or receivers C are divided by central longitudinal and transverse partitions *a a'*, which extend from the top to near the bottom thereof, into a number of spaces or cells, each of which is adapted to receive one of the well-known dinner-trays by which meals have heretofore been sent out. Each cell or compartment is covered by a removable lid, C', to prevent the escape of heat, or one lid may cover several cells. The dinner-trays are composed 65 of a tin frame provided with a handle at the top and with a number of dishes, which are arranged vertically one on top of the other.

The attendant can readily pass along the intermediate space between the receivers C to 70 any part thereof, and by removing the lid take out any one of the trays which he desires to deliver, the meals in the same being kept warm while in transit, so that they can be delivered in a perfectly warm state to families, whatever 75 be the distance from the central kitchen.

The wagon is provided with a hinged door, H, at the rear end, and with a step or steps, I, for conveniently gaining access to the tanks and refrigerator.

The receivers or tanks C are provided with discharge-pipes J, having stop-cocks J', for drawing off the water when the wagon is not in use.

The furnace is made of any suitable construction, the smoke being drawn off by a smoke-pipe, K, that terminates above the top of the wagon.

At both sides of the wagon, above the receivers, are arranged one or more shelves, L, 90 on which pies, fruit, and such other articles as do not require to be delivered in warm state are stored, so as to be readily taken down and delivered with the dinner-tray.

Ice-cream and other articles to be delivered 95 in a cold state are stored in the refrigerator, the door B' of which opens for this purpose into the central passage.

As but a small quantity of water is required in the bottom of each tank to keep the trays 100 warm, comparatively little weight has to be carried, which is of great advantage, as other-

wise the construction of the wagon would become too heavy and clumsy.

Having thus described our invention, we claim as new and desire to secure by Letters Patent—

1. A caterer's wagon having tanks or receivers adapted to be partially filled with hot water, the upper portions of said tanks being divided into compartments for the trays, said wagon being provided with a steam-boiler or other means for heating the water in the tanks, substantially as set forth.

2. A caterer's wagon provided with a refrigerator extending transversely across the body back of the driver's seat, and with two tanks or receivers extending along the sides of the wagon from the refrigerator to the rear end, said receivers being divided by suitable partitions into a number of spaces or cells for the trays, said wagon being also provided with means whereby the trays in the receivers are

kept warm by steam or hot-water circulation, substantially as and for the purpose set forth.

3. A caterer's wagon having a refrigerator arranged transversely across the wagon, back of the driver's seat, closed receivers running along both sides of the wagon from the refrigerator to the rear end thereof, said receivers having longitudinal and transverse partitions, so as to form cells or spaces for the trays, suitable means to heat the trays in the receivers, and shelves arranged at both sides of the wagon, substantially as and for the purpose described.

In testimony that we claim the foregoing as our invention we have signed our names in the presence of two subscribing witnesses.

EMIL M. PERHÁCS.
FRANZ NEUMÜLLER.
